SEATING UNIT

Leif Blodee, Holland, Mich., assignor to American
Seating Company, Grand Rapids, Mich.

Filed Feb. 14, 1972, Ser. No. 226,397

Term of patent 14 years

Int. Cl. D6—01

U.S. Cl. D6—41

FIG. 3

FIG. 4

FIG. 7

FIG. 8

FIG. 9

FIG. 10

FIG. 11

FIG. 12

FIG. 13

FIG. 14

FIG. 15

FIG. 16

FIG. 1 is a front perspective view of a seating unit showing my new design;

FIG. 2 is a rear perspective view;

FIG. 3 is a top plan view;

FIG. 4 is a front elevational view;

FIG. 5 is a front perspective view of a seating unit showing a second embodiment of my new design;

FIG. 6 is a rear perspective view thereof;

FIG. 7 is a front perspective view of a seating unit showing a third embodiment of my new design;

FIG. 8 is a rear perspective view thereof;

FIG. 9 is a front perspective view of a seating unit showing a fourth embodiment of my new design;

FIG. 10 is a rear perspective view thereof;

FIG. 11 is a top plan view thereof;

FIG. 12 is a front elevational view thereof;

FIG. 13 is a left side elevational view of the seating unit shown in FIG. 1;

FIG. 14 is a left side elevational view of the seating unit shown in FIG. 5;

FIG. 15 is a left side elevational view of the seating unit shown in FIG. 7; and

FIG. 16 is a left side elevational view of the seating unit shown in FIG. 9.

I claim:

The ornamental design for a seating unit, as shown and described.
